UNITED STATES PATENT OFFICE

2,383,594

ELECTROMAGNETIC SOUND REPRODUCER

Walton De Verter, Chicago, Ill.

Application January 2, 1943, Serial No. 471,132

2 Claims. (Cl. 179—1)

This invention relates to sound reproducers or loud speakers, more particularly to electrodynamic sound reproducers in which a movable dynamic or voice coil, excited with sound-representing or voice currents, is provided for interaction with an intense unidirectional magnetic field, and the invention has for an object the provision of improved sound reproducers of this character.

In the usual radio receiver or electric phonograph adapted for operation on commercial alternating current, the field producing winding of the electrodynamic sound reproducer associated with such apparatus is excited with unidirectional pulsating current, such as may be obtained from the rectifier circuit utilized for supplying the plate and grid energy to the amplifier tubes of the receiver or phonograph. The fluctuations or periodic variations of the magnetic field produced by such excitation have been found to produce, by interaction with the dynamic coil, an undesirably intense and annoying hum in the loud speaker.

In order to minimize or substantially eliminate this undesirable hum, it has heretofore been proposed to provide such sound reproducers or loud speakers with a second or bucking coil disposed in the magnetic field and connected directly in series with the voice coil and the source of sound-representing or voice currents. This second series coil is of opposite polarity to the voice coil, and therefore tends to produce in the voice coil voltages opposite in phase to those induced directly in the voice coil by the fluctuations of the magnetic field.

While in most respects electrically satisfactory, mechanical difficulties are encountered in the economic construction and proper location of such series bucking coils. Ordinarily such series coils are wound on separate forms or tubes and may be placed either over the core of the loud speaker, or inside of the field winding, or around the outer periphery of the field winding. In any event, the series coil, which must carry all of the voice or sound-representing currents supplied to the dynamic coil, must be formed of relatively heavy wire, and thus difficulties are introduced into fabrication and excessive costs are encountered. In addition, the heavy wire series coil takes up space which could otherwise be devoted to better use in constructing the loud speaker. Accordingly, something is yet to be desired in providing compact, inexpensive and electrically satisfactory loud speakers of this character, and it is a further object of this in-

vention to provide improved hum-bucking or minimizing means in loud speakers of the electrodynamic type.

In carrying out the invention in one form, a loud speaker is provided having the usual field producing winding and a dynamic or voice coil disposed in the magnetic field and energized from a suitable source of sound-representing currents. A second or bucking coil is likewise disposed in the magnetic field and connected in parallel circuit relation to the dynamic coil across the source of sound-representing currents, so as to form a local series circuit which contains the two coils. The polarity of the bucking coil is opposite to that of the dynamic or voice coil so as to oppose and minimize currents induced in the voice coil by fluctuations in the strength of the magnetic field. The parallel bucking coil, which may be designed so as to carry only a small component of the sound-representing currents supplied to the voice coil, may be formed of very fine gauge wire, and the area occupied thereby and the costs of fabrication and materials are considerably less than for the heretofore known series bucking coils.

For a more complete understanding of the invention, reference should now be had to the drawing in which the single figure is a diagrammatic representation of a sound reproducer or loud speaker embodying the present invention.

In the drawing, the invention is shown as embodied in a loud speaker comprising the usual horn 10, a field winding 11, a dynamic or voice coil 12, and a bucking coil 13. Since the magnetic circuit of the sound reproducer is entirely conventional, only the electrical circuits have been shown.

The field winding 11 is connected, as shown, to a pair of terminals 14 which may represent a source of periodically fluctuating unidirectional current such as may be obtained from the usual rectifier circuit. The voice coil 12 is connected to be supplied with sound-representing currents from the secondary winding 15 of a suitable transformer 16, the primary winding 17 of which is connected to suitable terminals 18 which may, for example, be the output terminals of an amplifier system such as is contained in a radio receiver or an electric phonograph. The voice coil 12 is of course disposed in the intense magnetic field produced by the winding 11, so that upon the flow of sound-representing currents through the voice coil 12, movement thereof will be produced and the voice coil may be connected in any suitable manner to the diaphragm of the horn 10.

As shown, the parallel bucking coil 13, which is also disposed in the magnetic field produced by the winding 11, is connected across the voice coil 12 in parallel circuit relation thereto with respect to the source of sound-representing currents constituting the secondary winding 15 of the transformer 16. The two windings 12 and 13 are preferably so constructed and correlated that only a small component of the voice-representing currents from the transformer winding 15 flows through the bucking coil 13.

In addition to the parallel circuit, the two coils 12 and 13 constitute a local-series circuit which may be traced from one terminal of the winding 13, through the conductors 19 and 20, the coil 12, and the conductors 21 and 22, to the opposite terminal of the coil 13. The coils 12 and 13 are, as previously indicated, of opposite polarity so that the inductive effect of the magnetic field on these coils tends to produce, in the two coils of the local series circuit, voltages and currents of opposite polarity. Thus the direction of the voltages and currents induced in the coil 13 is represented in the drawing by the broken arrows extending about the local series circuit, while the direction of the voltages and currents induced in the coil 12 is represented by the solid line arrows extending about the local series circuit.

By properly adjusting the locations of the respective coils 12 and 13 and the electrical characteristics of each coil, it is possible substantially to eliminate or greatly minimize the flow of current in the local series circuit due to the inductive effect of the fluctuations in the magnetic field produced by the winding 11. Consequently, the interaction between the magnetic field and the voice coil 12, due to such fluctuations, is substantially eliminated and the hum, which would otherwise appear in the horn 10 of the loud

speaker, is reduced to a satisfactorily low value.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. In an electrodynamic sound reproducer, the combination of a field winding energized by unidirectional current to produce a magnetic field, a source of sound representing current, a dynamic coil connected across said source and disposed in said magnetic field, and a bucking coil disposed in said field and connected across said dynamic coil in parallel relation thereto with respect to said source to form a local series circuit including said two coils, said bucking coil and said dynamic coil being of opposed polarity with respect to the inductive effect thereon of fluctuations in the strength of said magnetic field.

2. In an electrodynamic sound reproducer, the combination of a field winding energized by unidirectional current to produce a magnetic field, a source of sound representing current, a dynamic coil connected across said source and disposed in said magnetic field, and a bucking coil disposed in said field and connected across said dynamic coil in parallel relation thereto with respect to said source to form a local series circuit including said two coils, said bucking coil and said dynamic coil being of opposed polarity with respect to the inductive effect thereon of fluctuations in the strength of said magnetic field, the bucking coil being arranged to produce in said local series circuit, by the inductive effect thereon of variations in the strength of said field, potentials opposite in polarity to the potentials induced in said dynamic coil by said variations.

WALTON DE VERTER.
